SPINNER FOR A STRING TYPE WHIRLING TOY

Anthony J. Parente, 2204 E. Washington Lane,
Philadelphia, Pa.

Filed Apr. 17, 1964, Ser. No. 79,535

Term of patent 14 years

(Cl. D34—15)

FIG. 1

FIG. 2

FIG. 3

FIG. 1 is top plan view of a spinner for a string type whirling toy embodying my new design, the bottom plan view being the same.

FIG. 2 is a side elevational view of the toy, the opposite side being the same.

FIG. 3 is an end perspective view of the toy, the opposite end perspective view being the same.

I claim:

The ornamental design for a spinner for a string type whirling toy, as shown and described.
